THOMAS CLARKSON MC CONKEY AND GEORGES PICARD, OF MONTREAL, QUEBEC, CANADA, ASSIGNOR TO THE B. J. COGHLIN COMPANY LIMITED, OF MONTREAL, QUEBEC, CANADA, A CORPORATION

SPRING CONTROL

Application filed July 26, 1927. Serial No. 208,641.

This invention relates to vehicle springs and more particularly to providing means to restrain the rebound of the spring following its flexure, and forming a part of the leaf 5 construction.

Various devices have been employed to restrain the rebound of vehicle springs in the form of attachments, which have been applied to the spring, whereas in this invention the 10 means employed forms a part of the leaf construction adjusted by a clamp.

The invention consists in providing longitudinally extended arched ends to one of the intermediate leaves of a spring, with clamps 15 embracing the arches and the main leaf, which enable the leaves to be distorted or ridged within the arch and the tension and friction between such leaves to be adjusted.

I am aware that a vehicle spring with one 20 of its leaves arched near its ends has been employed in combination with an adjacent leaf having ridges made to fit within the arches. See United States Patent No. 1,495,177. May 20th, 1924.

25 In this invention however, the arched ends of the leaf are employed in combination with adjustable clamps, forming a two point contact on one side of the spring and an intermediate point of contact below the spring, 30 whereby the leaves below the arches may be distorted or ridged within the arches, to the degree required to restrain endwise movement between the leaves so distorted or ridged.

35 I am also aware that spring bows with clamps have been employed to increase the friction between the leaves, but in this invention the arches have their end edges bearing vertically on the adjacent leaf and do not 40 extend lengthwise when clamped, as is always the case with spring bows.

Reference is made to the accompanying drawing in which:—

45 Fig. 1 shows a side view of the spring showing the device at each end.

Fig. 2 is a vertical longitudinal section through the device.

Fig. 3 is a cross section on the line 3—3 of Fig. 1.

50 The spring 1, of the semi-elliptic type, has

a main leaf 10, terminating in eyelets, a second leaf 11, extends towards the eyelets, the third leaf 12, has an arch 13, at each end, with the edge 14, bearing on the surface of the leaf 11. The arch 13 which forms the rigid 55 element of the leaf 12, is preferably made with a groove or indentation 15 to receive the clamp 2. The clamp is shown as a U bolt 2, seats in the indentation 15, with its threaded ends extended through the perforated plate 60 3. The nuts 20 preferably are lock nuts. The arch 13 with the adjusted clamp 2 form a rigid two point contact on one side of the spring and an intermediate point of contact 65 on the other side.

With a construction such as above described, the clamp can be adjusted to produce a distortion or ridging of the leaves 10 and 11 over the plate 3 and between the two point contact of the arch 13. By the tightening 70 of the clamp the frictional resistance between the leaf 12 and its edge 14, and the adjacent leaf 11 is increased, while the distortion of the leaves 10 and 11 effects a binding or gripping action between them which interferes with their endwise movement independently.

When the spring is lengthened by downward pressure of its center or upward pressure of its ends, the leaves tend to slide on one another, but are restricted by the distortion or ridging of their parts within the clamp and arch, according to the degree of adjustment. On the rebound, the same restriction operates to limit the extent of the 80 rebound. The device also restrains any tendency to vibrate or shake. The violence of wheel shocks is greatly diminished when used on motor vehicles, and smoother running is obtained by a simple and inexpensive 85 shock absorber.

What is claimed is:

1. In a shock absorber, a leaf spring having an intermediate leaf arched at its end, its end edge bearing vertically on the adjacent leaf, adapted to form a two point base against the adjacent leaves thereunder, and a clamp about the arch and the said leaves. 90

2. In a shock absorber, a leaf spring having an intermediate leaf arched at its end, its 100

end edge bearing vertically on the adjacent leaf, adapted to form a two point base against the adjacent leaves thereunder, and an adjustable clamp about the arch and the said leaves adapted when adjusted to bind the leaves between the points of the arch, and when the spring is flexed, to increase the binding action.
